MOLDING MACHINE AND MOLD FOR CENTRIFUGAL CASTING OF ANNULAR BODIES

Nelson W. Webb, Montclair, N. J., assignor to Encor Corporation, Belleville, N. J., a corporation of New Jersey

Application August 2, 1940, Serial No. 349,926

2 Claims. (Cl. 22—65)

The present invention relates to an improvement in molding machines and molds for centrifugal casting of annular bodies, particularly in the form of a centrally apertured discus plate, such machines and molds being of the general type disclosed in the U. S. Patent to Walter Bremicker 2,159,073, dated May 23, 1939. In this type of machine the centrifugal casting molds consist of two separable mold parts having an annular molding cavity, and rotatable about a horizontal axis, the molten metal being poured into the mold through a central opening in the outer mold part, and whereby through centrifugal action created through the rotation of the mold an annular plate is cast having a central hole therein.

These molds have involved considerable trouble and expense in their operation, in order to produce cast plates of substantially constant accurately controlled thickness, whether such plates be of uniform thickness throughout, or of a predetermined differential thickness, this being due to the heat of the molten metal which causes the mold parts to bulge and gradually assume concave inner faces. In other words they gradually assume the shape of a "Belleville" washer, since they are clamped together on their outside rims but are free to diverge from one another at their centers due to thermal strains, these thermal strains being set up due to the steep temperature gradient between the side of the mold against the molten metal and the side of the mold against room temperature. The larger the diameter of the mold the more severe is this bulging effect each time a casting is made, and in practice it has been found that in molds making a casting of 28 inches in diameter, the casting was $\frac{1}{4}$ inch thicker in the center than at the periphery after only about sixty castings were made. Obviously these sixty castings would vary in thickness between the proper thickness of the first casting and the increased center thickness of the sixtieth casting, and as such castings are intended to be rolled flat and then spirally cut by a circular shear into a length of sheared wire to be drawn into finished wire the uncontrolled variation in the castings produced variations in the quality and density of the wire. In the case of molds of a type not disclosed in the Bremicker patent, and in which the molding cavity is purposely made of increased thickness toward the center in predetermined direct proportion to, and to compensate for, the differential in the density between the inner and outer portions of the annular casting due to centrifugal

action, the density becoming equalized upon flat rolling of the plate, this uncontrolled variation in the thickness of the mold cavity not only produced variations in density in the finished wire but nullified the purpose of such improved type of mold to produce wire of uniform density. It has been the practice in order to control the casting thickness to a practical degree to dismantle the mold after a comparatively short run and machine the inner surfaces to their original shape, but the objection to this is that the expense and time consumed is considerable and the change in the thickness dimensions of the inner and outer portions of the mold parts increased the tendency to bulge during the casting process, so that the runs after each reconditioning machining operation were gradually smaller, and the castings were subjected to an increasing differential effect in cooling after the casting operation. In this connection it is desirable that the molds be of a thickness to facilitate rapid cooling of the cast plates. However, experiment has shown that even when the molds are made extremely thick and/or of special resistant metal the bulging action still takes place.

It is an object of the present invention to provide a centrifugal molding machine in which the mold parts each comprise double-faced plates having identical half-mold cavities in each face, and to provide means whereby these mold parts may be reversed after each casting operation, so that the cavities at each side are alternately inwardly and outwardly disposed. As a consequence the bulging effect of one casting operation, which is only to a very small degree and insufficient to materially effect the plate being currently cast, will be compensated for during the succeeding casting operation, the mold parts thereupon bulging in the opposite direction from the direction of bulging during the first casting. Inasmuch as the mold parts must be separated in order to remove the casting the reversal does not involve any increase in labor or time, and to this end the machine includes reversing carriers for the two mold parts by means of which they may be readily moved into separated relation and thereupon individually reversed and again brought into cooperative relation in the machine.

With the above and other objects in view, embodiments of the invention are shown in the accompanying drawing, and these embodiments will be hereinafter more fully described with reference thereto, and the invention will be finally pointed out in the claims.

In the drawing:

Fig. 1 is a front elevation of a centrifugal casting machine according to the illustrated exemplary embodiment of the invention.

Fig. 2 is a side elevation of one end of the machine and showing the centrifugal mold at this end in vertical section, and showing in dot-and-dash lines the position of one of the mold parts during the reversal operation.

Fig. 3 is a view partially in side elevation and partially in section of the two-part mold.

Fig. 4 is a similar view of a modified form of two-part mold in which the mold cavity is shaped to cast a plate increasing in thickness toward the center.

Similar reference characters indicate corresponding parts throughout the several figures of the drawing.

Referring to the drawing, the casting machine is mounted upon a base 10, one end of which is illustrated, the other end being identical and carrying upon the mold supporting shaft another centrifugal mold unit similar to that illustrated. With this type of double-mold machine two plates may be cast simultaneously, or a plate cast at one end while the mold at the other end is being cooled, provided with mold dressing, and otherwise prepared for casting another plate. It will be understood however that the invention is not limited to this particular type of machine, but may be incorporated in single mold types.

A mold driving shaft 11 is journaled at each end of the base 10 in a bearing block 12 and carries a pulley 13 driven by a belt 14 from a pulley 15 provided on an upper counter-drive shaft 15^a journaled at each end in a bearing fixture 15^b mounted upon a frame 16 supported upon each end of the base 10, the shaft 15^a being driven from any suitable source of power.

The shaft 11 projects at each end, and has keyed thereon the hub 17 of the circular mold plate carrier 18, which is provided at its rim with a cylindrical flange 19 having a slot 20 at one point in which the transporting and manipulating supporting eyes of the mold plates are engaged, as will presently more fully appear. Upon the inner wall of the mold carrier there is provided an annular seating rib 21 inwardly spaced from the rim 19 and provided at its outer periphery with a beveled seating surface 22.

The two-part mold consists of an inner periphery rimmed diaphragmatic mold plate 23 and an outer peripherally rimmed diaphragmatic mold plate 24, the inner mold plate 23 being provided at each of its faces with a mold cavity forming recess 25, the outer wall 26 of which is beveled in correspondence with the beveled bearing surface 22, so that in the assembled relation in the plate carrier 18 the wall surface 26 wedgingly seats upon the seating surface 22, while the recess 25 and the wall 26 at the other side constitute the face and outer peripheral edge of one-half of the mold cavity. The central area of the plate 23 is out of contact with the central area of the mold carrier defined by the annular seat 22, so that there is no restriction of the bulging action which takes place in the plate 23 during the casting operation, and as will hereinafter more fully appear. The rim of the mold part 23 is provided at each side with a projecting shoulder flange 27 forming an annular pocket in which the rim of the outer or cover mold plate 23 is adapted to seat. The outer mold plate 24 is also provided at each face

with a recess 28 having a peripheral wall 29 which corresponds exactly to the recess 25 and wall 26 of the plate 23, the diameter of the plate 24 however being less than the diameter of the plate 23 and equal to the diameter of the seating pocket formed by the flange 27, so that it seats therein in centralized relation and whereby the inwardly disposed recesses 25 and 28 of the two plates constitute the annular mold cavity.

The plate 24 is provided centrally with the hole 30 into which the pouring spout 31 projects, molten metal being poured into this spout which flows downwardly into the centrifugal mold to form an annular plate casting. It will be understood that the pouring spout 31 is mounted upon a suitable fixture, as for instance a roller carrier or a swinging arm, so that it can be readily moved into and out of place respectively during the casting operation of the mold, and the opening and reversing of the mold parts.

The two mold parts are secured in the mold carrier by a series of bolt studs 32 having retaining lugs 33 mounted thereon and which are tightened against the outer surface of the rim 19 of the carrier and the outer surface of the rim of the outer or cover plate mold part 24 by means of nuts 34. The mold parts 23 and 24 are respectively provided with eye members 35 and 36 which project into the open space 20 of the rim 19, and which are adapted to be engaged by the conveyer means, presently to be more fully described, for removing the mold parts from the mold carrier.

Above the machine there is mounted an inverted T-shape trolley track member 37 carrying a pair of roller conveyer members 38 and 39 upon which are suspended the respective conveyer hook members 40 and 41 connected thereto by turn-buckles 42 and 43, and which hook members are adapted to be brought into engaging relation with the eye members 35 and 36.

Upon completion of the molding operation the mold is first disposed so that the eye members 35 and 36 are at the top, as shown in the drawing, and thereupon the lugs 33 are disengaged by backing off the nuts 34, the two hook members 40 and 41 being first engaged with the respective eyes 35 and 36 of the two mold parts. The mold parts are thereupon moved outwardly from the mold carrier and are then separated to allow the cast plate to drop therefrom, it being understood that a suitable interval may transpire before separating the mold parts to allow the cast plate to cool for a suitable period if this is found to be desirable.

The two mold parts are thereupon reversed by individually turning them by means of the turn-buckles of the conveyer, so that the recesses 25 and 28 which during the preceding molding operation were disposed inwardly and constituted the molding cavity are disposed outwardly. Before reversing the cavity surfaces may have a suitable mold dressing applied if this is found to be desirable. The recesses 25 and 28 which were outwardly disposed now constitute the molding cavity. The two mold parts are thereupon moved into relation with the mold carrier 18 and are clamped in place by means of the lugs 33 and the nuts 34, the hooks 40 and 41 are disconnected, and the machine is ready for the next casting operation.

By thus alternating the molding faces of the two diaphragmatic plates the bulging action

which takes place through the differential thermal strains set up by the steep temperature gradient between the inner and outer mold surfaces is compensated for by the succeeding molding operation, the surfaces which are bulged outwardly by one molding operation being reversed so that they bulge inwardly preparatory to the next molding operation, and which next molding operation causes them to bulge outwardly again. By thus reversing the plates after each molding operation the bulge is continually equalized, and as the degree of bulge during a single casting is not sufficient to materially affect the thickness of the plate the mold will continue to produce satisfactory uniform castings to any desired quantity, and with a considerable saving in time and production costs.

In Fig. 4 I have illustrated a modified form of the mold plate in which the recesses 25^a and 28^a are slightly inclined toward the center so that the mold cavity produces a plate which is of gradually increasing thickness toward the center. The purpose of this is to compensate for the differential in density in the material between the inner and outer peripheries of the cast plate due to the centrifugal action which causes the metal at the outer periphery to become denser from the weight of the metal building up at the inner periphery. The cast plate is thereupon adapted to be rolled to uniform thickness to equalize the differential density.

I have illustrated and described preferred and satisfactory embodiments of the invention, but it will be understood that changes may be made therein, within the spirit and scope thereof, as defined in the appended claims.

Having thus described my invention, what I claim and desire to secure by Letters Patent is:

1. In a molding machine for the centrifugal casting of annular centrally apertured discus plates, a vertically disposed rotatable mold carrier rotatable about a horizontal axis, a two-part centrifugal casting mold comprising a pair of circular mold parts, each consisting of a circular diaphragmatic plate having complementary and identical faces at each of its sides and a circular

rim surrounding said plate and projecting to an equal extent at each side thereof to constitute the peripheral wall of a circular mold recess at each side, the recesses of both of said mold parts being of the same diameter, and each of said mold parts being individually reversable to dispose the mold recess at either of its sides in either facing or non-facing relation to the other mold part, one of said mold parts having an opening 10 for receiving molten metal, and means for removably securing said pair of mold parts to said carrier with the mold recesses at their facing sides constituting a circular mold cavity and the mold recesses at their other sides constituting spaces 15 in which the diaphragmatic plates may bulge during the casting operation.

2. In a molding machine for the centrifugal casting of annular centrally apertured discus plates, a vertically disposed rotatable mold carrier rotatable about a horizontal axis and having an annular beveled seating rib formed upon its forward face, a two-part centrifugal casting mold comprising a pair of circular mold parts, each consisting of a circular diaphragmatic plate having complementary and identical faces at each of its sides and a circular rim surrounding said plate and projecting to an equal extent at each side thereof to constitute the peripheral wall of a circular mold recess at each side, the recesses of both of said mold parts being of the same diameter and the peripheral wall of each of said recesses being beveled and adapted to constitute an annular seat for engagement with said annular beveled seating rib, and each of said mold parts 20 being individually reversable to dispose the mold recess at either of its sides in either facing or non-facing relation to the other mold part, one of said mold parts having an opening for receiving molten metal, and means for removably securing said pair of mold parts to said carrier with the mold recesses at their facing sides constituting a circular mold cavity and the mold recesses at their other sides constituting spaces in which the diaphragmatic plates may bulge during the casting operation.
